ABSTRACT

A system for supplying fuel to internal combustion engines by medium pressure injection including a pressurized fuel tank, a specially designed fuel pump and an electromagnetic fuel injector. The pump is a diaphragm-type pump of smaller diaphragm surface and increased spring pressure compared to conventional diaphragm-type fuel pumps. It is designed to provide an output fuel pressure at substantially that level necessary for feeding the injector thus obviating the necessity for a pressure regulator.

SYSTEM FOR SUPPLYING FUEL TO INTERNAL COMBUSTION ENGINES

FIELD OF THE INVENTION

The present invention relates to a system for supplying fuel to internal combustion engine by means of a fuel injector, and more particularly to an improved pump for supply fuel from a storage tank to the injector.

BACKGROUND OF THE INVENTION

All known systems designed to control the fuel feed in an internal combustion engine perform three functions: supply, regulation and control of flow.

The "supply" function can be accomplished either by means of a pump, usually of the diaphragm type, operating at a rather low pressure of the order of 200 g/cm², or by a pressurized tank which creates a still lower pressure level (20 to 30 g/cm²) or by a volumetric pump operating at a pressure level of the order of several kilograms/cm².

The "regulation" function can be accomplished either by means of a constant level (float) chamber or by means of a pressure regulator, possibly associated with a discharge valve.

The "control of flow" function can be accomplished by a fuel line which allows an amount to pass which is a function of several parameters: pressure, cross-section and opening time. Preferably, one of these parameters is controlled and the others remain fixed.

Thus, there is always a fuel supply system consisting of a pump, a pressure-regulating element which ensures regulated fuel pressure, and a control element which serves to measure the amount of fuel fed into the cylinder.

For the sake of an example, we can mention the following types of systems:

1. The conventional fuel line leading to the carburetor where the successive functions are carried out by; a diaphragm pump (feed)

a constant-level chamber (regulation)

a jet (control of flow)

2. The fuel injection system with electromagnetic control, where the successive functions are carried out by:

the high-pressure volumetric pump (feed)
a discharge valve plus regulator (regulation)
a controlled injector (control of flow).

3. The fuel line with a carburetor and pressurized tank where the successive functions are accomplished by:

a pressurized tank (feed)
a constant-level chamber (regulation)
a jet (control of flow).

10 In all of these systems, presented for the sake of examples, there is a physical dissociation between the first two functions due to the disproportion between the feed pressure and the required regulated pressure.

In conventional fuel lines supplying a carburetor of type 1 hereinabove, the properties demanded of the pump mainly include ensuring flow at sufficient pressure for the fuel to enter a constant-level chamber which is generally located slightly above the pump, and to limit the feed pressure when the jet is delivering a small volume so as not to disturb the level in the float chamber.

In known fuel lines of type 2 hereinabove, the pump pressure is much greater (possibly at least three times as great) than the average pressure required to feed the injectors, and two pressure-limiting devices with returns to the tank are necessary.

SUMMARY OF THE INVENTION

The principal object of the present invention is to provide a simplified fuel line which supplies gasoline to an engine whose carburetion is controlled by an orifice such that:

1. The profile is fixed (needle-projection and seat).

2. The cross-section of the passageway is variable and controlled (opening time and the cross-section versus travel of the needle relationship).

3. The downstream pressure is known (depression in the intake nozzle).

4. The upstream pressure is known and regulated to a constant value, with the pressure being created by a diaphragm pump connected mechanically to the crank-shaft of the engine. Its function is simultaneously to ensure feed to the controlling element (electromagnetic injector) and to ensure a constant pressure in the fuel line.

The following comparative table summarizes the above.

	Conven. auto carburetor FIG. 3	Conven. Injection FIG. 4	Conv. motorcycle carburetor	Injection in accord. w/invention, FIG. 6
Feed	Diaphragm Pump	Volumetric Pump	Pressurized tank	Pressurized tank Special Diaphragm pump
Regulation	Constant level chamber	Regulator	Constant level chamber	
Control of flow	Upstream Pressure Downstream Pressure Cross-section	Constant Variable depress. in throat of Venturi	Constant	Constant Variable depress. in throat of Venturi
Time		Lifting time of adjustable needle		Variable opening cross-section Lifting time of adjustable needle

Hence, the invention consists in achieving a novel combination of a pressurized tank with a special diaphragm pump, designed, on the one hand, to function as a feed from said tank, and, on the other hand, for the purpose of supplying an injector at a constant pressure, as is always necessary, but without using a regulating element. The injector is advantageously in conformity with the following patent applications of the assignee:

French Pat. No. 2,205,111 for an electronic control and monitoring system for the feed of fuel to two-cycle fuel injection engines; and

French Pat. No. 2,206,795 for improvements made to fuel injectors for engines; both of which are hereby incorporated by reference.

Such a fuel supply line is characterized by a single average pressure level between the feed element and the control element, without any additional element for regulating the pressure.

A novel feature of the fuel line thus conceived consists in the different operating conditions of the principal element, i.e., the pump.

BRIEF DESCRIPTION OF THE DRAWINGS

The invention will be discussed in greater detail with reference to the attached sketches:

FIG. 1 is an explanatory graph of fuel pressure as a function of flow for the special diaphragm pump in accordance with the present invention in comparison with a conventional diaphragm pump.

FIG. 2 is an explanatory graph showing the available flow from the pump in accordance with the present invention as a function of the number of strokes per minute of the engine for a given pressure, and the maximum demand of the engine.

FIG. 3 is a diagram indicating the pressures in the various portions of a conventional automobile carburetor fuel supply system.

FIG. 4 is a diagram indicating the pressures in the various portions of a conventional injection fuel supply system.

FIG. 5 is a diagram indicating the pressures in the various portions of a conventional carburetor with pressurized tank fuel supply system.

FIG. 6 is a diagram indicating the pressures in the various portions of a fuel supply system in accordance with the present invention; and

FIG. 7 represents as an example, in axial section, of a diaphragm feed pump in accordance with the invention.

DESCRIPTION OF PREFERRED EMBODIMENTS

As is clearly shown by the graph in FIG. 1, the characteristic curve (at constant velocity) of the pressure as a function of the flow shows a favored zone (c) where the pump pressure remains constant while the flow remains below a certain level D.

It is this property which is applied to the supply of the injectors by means of the present invention.

This zone narrows when the velocity drops but, fortunately, the needs of the engine follow the same law and consequently it is possible to adapt the characteristic curve of the pump to the demand of the engine, as indicated by the graph in FIG. 2, where the available flow from the pump for various constant output pressures, on the one hand, and the maximum demand of the engine on the other hand are represented as a function of

the number of strokes per minute. There are four elements of a diaphragm-type fuel pump which must be adjusted for each application in order to have the optimum compromise:

- 5 a. the force of the spring, which acts on the pressure;
- b. the effective area of the diaphragm, which affects the flow and the pressure;
- c. the travel of the diaphragm, which also affects the flow; and
- 10 d. the mechanical linkage between the crankshaft and the pump, which affects the relative positions of the curves.

The pump designed according to the present invention, therefore, consists, on the one hand, of a diaphragm with a reduced area, in an average ratio of 3:1 (for example) in comparison to a conventional pump, and on the other hand a return spring for this diaphragm which is essentially more rigid than the conventional spring and which exercises a force which is on the average twice as great.

In the pump according to the invention, the effective area of the diaphragm is at most 400 square millimeters and the force exercised by the return spring is at least 3 kg. As an example, a pump designed for a 350 cubic centimeter motorcycle engine has an effective diaphragm area of 300 square millimeters and the force exercised by the spring amounts to 6 kg. The pump output pressure is 2 kg/cm² and the flow is 12 liters/hour for 2,500 strokes per minute.

25 30 For the sake of comparison, a conventional pump designed for a 1,000-1,500 cubic centimeter automobile engine has an effective diaphragm area of about 1,200 square millimeters and the spring exercises a force of 1.5 kg. The pump output pressure is 130 grams/cm² and the flow is 25 liters/hour at 1,000 strokes per minute. For the sake of an example, in FIG. 1 we have shown for 2,000 strokes/minute the characteristic curve (a) for the flow versus pressure for such a pump plotted with a dot-dash curve, and the characteristic curve (b) of a classic pump plotted with a dashed line.

35 40 On the other hand, since the diaphragm has a smaller area, but the stroke is comparable to that of conventional diaphragm pumps, the volume displaced with each cycle is low, although it is sufficient to satisfy the demand of the engine, and the gear ratio between the crankshaft and the pump is therefore selected appropriately. This low volume, however, still does not allow the pump to assume in a satisfactory fashion (especially during starting), the function of aspiration from a tank located below the level of the pump and the pump is therefore combined with a tank located above the pump level.

45 50 Such a feed system at medium pressure for an electromagnetic injector has unquestionable advantages as follows:

- 55 1. Simplicity of design of a diaphragm pump relative to a fuel pump of the paddle type, with rollers or pistons, where tightness is obtained by means of accurate machining which is costly.
- 60 2. Regulation by the pump itself, doing away with any discharge valve associated with a return line and intended to reduce the pressure level to a lower level, called the regulated level.
- 65 3. Direct and mechanical connection to the crankshaft which makes it possible to have independence relative to a battery, which may not exist in the vehicle, with the application of energy to this linkage corre-

sponding exactly to the pumping needs, and the elimination of a safety element which is normally required in the event of electrical feed in order to avoid useless pumping at very low speeds.

Means will preferably be included to eliminate gasoline vapor blocks in the system in which the reservoir is located above the level of the pump. The lines will be provided with conventional means; the pump advantageously situated at a level which is very slightly above that of the injectors and a very low-volume bypass (very small diameter tube) which will connect the output and input.

This pump has associated with it a flexible hose which is used to eliminate the slight fluctuations in pressure in the line relative to the average pressure level, playing the role of a capacitor, since these slight fluctuations can occur when the injectors are working and when the pump diaphragm spring is put under tension.

This resilient hose connected to injector 26, is represented by 10 in FIG. 7, which shows a simple example of a modified diaphragm pump according to the invention.

A cam 11 cut in shaft 12 driven by the engine crank-shaft through the necessary reduction gears acts on a 25 push rod 13 which in turn moves a rocker arm 14. The latter deforms diaphragm 15 which, according to the invention, has a useful diameter which is significantly smaller than that of conventional diaphragms, its area being (for example) about three times smaller. The return spring 16 of this diaphragm is itself reinforced so as to exert a force which is about twice that of a conventional pump.

The intake nozzle is represented by 17 and the outlet nozzle is represented by 18. Valves 19 and 20 are associated respectively with each of these two nozzles.

Nothing will be changed in the invention if the function of the pressurized tank 22 is ensured by an auxiliary pump 24 (shown in broken lines because it is optional) which will furnish at the input of the special pump provided, a pressure level which is equivalent to that of this tank.

It will be obvious to those skilled in the art that vari-

ous changes may be made without departing from the scope of the invention and the invention is not to be considered limited to what is shown in the drawings and described in the specification.

What is claimed is:

1. A system for supplying fuel to internal combustion engines by medium pressure injection, comprising:
a fuel tank;
a fuel injector;
a diaphragm-type fuel pump means for supplying fuel from said tank to said injector, said fuel pump means having an inlet, an outlet, a diaphragm and a spring return means;
linkage means for driving said fuel pump at a speed proportional to that of the engine;
means for causing fuel from said fuel tank to enter the intake of said fuel pump means at a predetermined pressure; and
line means for directly connecting the output of said fuel pump means to said injector without interposition of any pressure regulating means;
wherein the effective diaphragm area in said fuel pump means is at most 400 square millimeters and the force exercised by said spring return means is at least 3 kg,
whereby the fuel pump means output pressure will remain substantially constant as the fuel pump means output flow varies from a substantially nil value up to a predetermined maximum value.

2. A system according to claim 1, wherein the output pressure of said fuel pump means is about 2 kg/cm².

3. A system according to claim 1, wherein said line means connecting said fuel pump means to said injector is resilient.

4. A system according to claim 1, wherein said means for causing fuel to enter the intake of said fuel pump means at a predetermined pressure comprises means for locating said tank above the level of said pump.

5. A system according to claim 1, wherein said means for causing fuel to enter the intake of said fuel pump means at a predetermined pressure comprises an auxiliary pump.
